Primary Examiner — Andrew Kerr(74) *Attorney, Agent, or Firm* — David L. Stott(57) **CLAIM**

The ornamental design for legs for an outdoor cooking station, as shown and described.

DESCRIPTION

FIG. 1 is an isometric view of the outdoor cooking station; FIG. 2 is a front view thereof; FIG. 3 is a rear view thereof; FIG. 4 is a left-side view thereof; FIG. 5 is a right-side view thereof; FIG. 6 is a top view thereof; and, FIG. 7 is a bottom view thereof.

The broken lines in the drawings represent portions of the outdoor cooking station that form no part of the claimed design.
